DESIGN FOR A GAS WATER-HEATER.

59,437.

Specification for Design.

Patented Oct. 18, 1921.

Application filed October 12, 1920. Serial No. 416,559. Term of patent 14 years.

To all whom it may concern:

Be it known that I, JOSEPH OSCAR SMITH, a citizen of the United States, residing at Los Angeles, in the county of Los Angeles and State of California, have invented a new, original, and ornamental Design for a Gas Water-Heater, of which the following is a specification, reference being had to the accompanying drawing, forming part thereof.

Figure 1 is a side elevation of a gas water heater showing my new design, and

Fig. 2 is a side elevation thereof taken at right angles to Fig. 1.

The essential feature of my design consists in providing upon a standard as indicated

in the drawings, a relatively high and narrow tubular or pipe-like heating column. The particular construction of the standard and connections may be varied and the details thereof are not essential to my design.

Having thus described my invention, I claim:

The ornamental design for a gas water heater substantially as shown and described.

Signed at Los Angeles, California, this 6th day of October, 1920.

JOSEPH OSCAR SMITH.
